(57) **CLAIM**

The ornamental design for a kitchen ventilation hood, as shown and described.

DESCRIPTION

This application is being filed together with two other kitchen ventilation hood applications by the same inventor on this same date. The other applications are 29/127,123 and 29/127,125.

FIG. 1 is an upper front right perspective view;

FIG. 2 is a lower front left perspective view;

FIG. 3 is a front elevational view; the other side is identical thereto;

FIG. 4 is a side elevational view; the other side is identical thereto;

FIG. 5 is a top plan view; and,

FIG. 6 is a bottom plan view.

Distinctive curves, a unique suspended structure and a “tool rail” running along the outer front edge of the kitchen ventilation hood.

The broken line showing of environmental structure is for illustrative purposes only and forms no part of the claimed design.
